UNITED STATES PATENT OFFICE.

JOHN STRAUB, OF ASHLEY, NORTH DAKOTA.

TAG.

Application filed August 26, 1925. Serial No. 52,610.

To all whom it may concern:

Be it known that I, JOHN STRAUB, a citizen of the United States, residing at Ashley, in the county of McIntosh and State of 5 North Dakota, have invented certain new and useful Improvements in Tags, of which the following is a specification.

This invention relates to tag holding devices and is especially designed for holding 10 shipping tags.

The primary object of this invention is the provision, in a manner as hereinafter set forth, of a holder designed to be attached to any article which has to be transported 15 from place to place, for removably holding upon the said article a tag setting forth the destination of the article and the point from which the same started upon its journey. This device is particularly adapted for use 20 upon such things as trunks, ice-cream tubs, soft drink cases, malt and cider casks, bread boxes, motion picture boxes, and all boxes and cans used to transport goods of all descriptions.

25 Another object of the invention is the provision, in a manner as hereinafter set forth, of a tag holder of the type described, having means for holding the corners of a tag and the central portion thereof so that 30 the indicia thereon may be easily read, and at the same time allowing the tag to be easily and quickly removed for replacement by another tag.

The invention contemplates the provision 35 of a plate member having the corners thereof turned inwardly and having slots formed through the curved portion connecting the inturned corner with the body of the plate. A securing prong or spur is carried by the 40 plate in the center thereof and this spur is adapted to be extended through the body of a tag and turned down over the face thereof to secure the tag in position. The corners of the tag are then extended through 45 the slot formed in the curved portion connecting the inturned corners with the body of the plate. The tag is thus securely held against accidental displacement. Integral- 50 ly formed attaching tabs are carried by the plate by means of which the same can be attached to any desired article.

A further and final object of this invention is the provision, in a manner as herein- 55 after set forth, of a tag holder of unique and simple design, strong and durable, and inexpensive to manufacture.

The invention will be best understood from a consideration of the following detailed description taken in connection with the accompanying drawing forming a part 60 of this specification, with the understanding that the invention is not confined to any strict conformity with the showing of the drawing but may be changed and modified 65 so long as such changes and modifications mark no material departure from the salient features of the invention as expressed in the appended claims.

In the drawings:

Figure 1 is a plan view of the holder embodying this invention with a tag carried 70 therein.

Figure 2 is a transverse section taken upon the line 2-2 of Figure 1 and,

Figure 3 is a section taken upon the line 75 3-3 of Figure 1.

Referring now to the drawing in detail wherein like numerals of reference indicate corresponding parts throughout the several views, the numeral 1 indicates a flat body 80 member formed of a plate of metal or other desirable material, and extending from each side of the plate are integral ears 2 through which apertures 3 are formed for the passage of securing elements, when the holder 85 is to be placed in position.

Each of the four corners of the plate 1 are inturned as shown, forming the overlying corner tongues 4, and cut through the bent or curved portion 5 which joins the tongue 90 4 to the body, are slots 6 which extend longitudinally of the bend as shown. These slots do not extend to the edge of the bent portion but are closed at each end as is also shown in Figure 1.

Secured at one end to the central part of the face of the plate 1 is a spring steel tongue 8 which is designed through its inherent spring qualities to lie flat against the face of the plate as shown. When a tag is to 100 be placed in position the tongue is forced upwardly and then projected through the tag after which it is released and will spring down upon the face of the tag as shown.

When the holder is in use or is to be 105 placed in use, securing members are passed through the apertures 3 of the ears 2 to maintain the holder in position upon the desired article. A destination tag is then placed in position to have the extended 110 spring tongue forced therethrough and when this tongue has swung down across the face

of the tag, the corners thereof are extended through the slots 6 beneath the tongues 4 and the tag is ready for use.

It will be readily seen from the foregoing description that a tag such as that shown in Figure 1 when placed in position in a holder of the type shown and described will be securely held and cannot become accidentally displaced or lost. At the same time little or no trouble is involved in removing this tag and replacing the same with a new one when desired.

Having thus described my invention what I claim is:—

1. A tag holder of the character set forth, comprising a plate body having each corner thereof turned inwardly over the face of the plate and further having a slot cut from the portion connecting the inturned corner with the body for the extension of the corners

of a tag therethrough, means for attaching the body to an article, and an engaging tongue carried by the body and adapted to pierce the tag and secure the same to the body.

2. A tag holder of the character set forth comprising a plate body, means whereby said body may be secured to an article, means forming an integral part of said body for holding the corners of an address card, and a tongue secured at one end to the face of said plate and having inherent means for causing it to normally press against the face of the plate to hold the central portion of said card thereagainst after being projected through the card.

In testimony whereof, I affix my signature hereto.

JOHN STRAUB
